SMITH F. KRUPP, OF ATLANTA, GEORGIA.

SPACING DEVICE FOR GIN-SAWS.

1,217,018.

Specification of Letters Patent. Patented Feb. 20, 1917.

Application filed March 31, 1916. Serial No. 88,061.

To all whom it may concern:

Be it known that I, SMITH F. KRUPP, a citizen of the United States, residing at Atlanta, in the county of Fulton and State of Georgia, have invented new and useful Improvements in Spacing Devices for Gin-Saws, of which the following is a specification.

This invention relates to spacing devices for gin saws and contemplates the provision of a ring with an unbroken or smooth surface together with means held by, forming a part of, or engaging the saws to serve as bearing means or contacting devices for the rings interposed between the saws. The improvement also contemplates the use of a projection at various points relatively to the saw body or at a suitable distance inwardly from the periphery of the latter and arranged in suitable series, either integral with or primarily separate from and fitted to the saws. These projections in series in relation to the saws engage the inner sides or surfaces of the rings and in some instances they may continuously extend through all of the saws, the essential feature of the invention being to provide the saws with ring supporting means which may be either a part of or primarily independent of the saws and engaging the latter to hold the rings in concentric relation to the shaft upon which the saws are mounted in the organization of a saw cylinder for gins of various types.

The improved spacing device or ring fully occupies the usual distance between the saws of a saw cylinder or has such width as to completely close the space between the saws at a distance inwardly from the peripheries of the latter and obviates the formation of a web between the periphery of the ring and the shaft which it surrounds. The spacing device also has an outer surface which is free of all projections or indentations and thereby avoids resistance to the air. The spacing devices or rings embodying the features of the improvement and having smooth outer surfaces will not generate currents of air; and fine leaf trash and dirt, sifting down from the roll box between the ribs, are prevented from being blown toward the brush and back into the lint. Moreover, gin saws as they are now constructed require hammering to make the material flat and in

addition after they have been finished and placed upon the shaft the edges have to be trained so that the entire periphery will run in the same plane and parallel to the plane of rotation. The improved ring spacer will be used without requiring any change in this saw preparation procedure, but within the circumference of the ring spacer the hammering operation may be omitted, the hammering being effected only along the edges of the saws. The improved ring spacer also maintains the saws in equidistant relationship and prevents the same from being sprung laterally to either one side or the other or being crowded by the cotton until they strike or rub against the gin ribs, and the improved spacer renders the gin saws more effective in their ginning operation relatively to the cotton or in operation in linters.

In the accompanying drawings several forms of the improved ring spacer and its supporting means are shown to illustrate the manner of carrying out the principle involved and to indicate that the invention is not confined within its scope to any particular means for accomplishing the result sought, but on the contrary is capable of variation within a wide range.

In the drawings:

Figure 1 is a longitudinal section taken through a portion of a saw cylinder and the saws thereon and showing the spacer and one form of supporting means therefor.

Fig. 2 is a transverse vertical section taken in the plane of the line 2—2, Fig. 1.

Fig. 3 is a detail perspective view of several gin saws, the improved ring spacer and a modification in the form of supporting means therefor, the several parts being separated.

Fig. 4 is a longitudinal vertical section of a portion of a saw cylinder showing the form of supporting means for the ring spacers as illustrated by Fig. 3.

Fig. 5 is a view similar to Fig. 4 showing a further modification in the supporting means for the ring spacers, one of the supporting means being illustrated in detail perspective at the right of the figure.

Figs. 6, 7 and 8 illustrate detail views of portions of ring spacers illustrating the manner of forming the joints between the ends thereof.

Fig. 9 is a detail view of a portion of ring that may be die cast or otherwise constructed without a joint.

The preferred form of the improved spacing device and support is shown by Figs. 1 and 2, and consists of a ring 5 of such diameter and width as to stand out a considerable distance from the saw shaft 6 and engage the saws at opposite edges so as to hold the latter positively the requisite and usual distance apart without liability of lateral bend or displacement of the saws. The supporting means for the rings, as shown by Figs. 1 and 2, consists of a plurality of projections 7 cut from and struck outwardly from each saw 8, the supporting or holding means 7 being bent at a slight angle to the one face of each saw, as shown by Fig. 1. The free ends of the supporting or holding means 7 are at such distance from the shaft 6 on which the saws 8 are mounted that the rings 5 will have their inner surfaces in engagement with said ends of the projections and be held in concentric relation to the shaft 6, as shown by Fig. 2. The end collar 9 of the saw cylinder is secured to the shaft 6 through a screw-threaded connection, as at 10, and is provided with an inwardly projected flange 11 which also engages or bears upon the projections 7 of the adjacent saw 8, as shown by Fig. 1. The spacing device or ring 5 is of such diameter that a comparatively small portion of each saw between the ring spacer and periphery 35 of the saw remains to be hammered, it being unnecessary to hammer or otherwise treat the portion of the saw between the inner surface of each ring and the shaft 6 on which the saw is mounted. It will also be seen that when the saws 8 are all grouped on the shaft 6, or the saw cylinder completed, a compact structure results from the interposition of the ring spacers 5 between the saws 8 and that the spaces between the 40 saws are materially closed by the rings and are also given a rigid support or resistance against bending and will as a consequence be maintained in true running position or centrally with relation to the spaces between the 45 saws. The ring spacers 5 are made of suitable metal and the ends thereof may be connected in a number of ways, such for instance as shown by Figs. 6, 7 and 8. In the form of joint shown by Figs. 6 and 8, the two ends of the ring spacer are lapped, as at 12, and are spot-welded or riveted; or as shown by Fig. 7 the two ends may be butt-welded, as at 13, or any other mode of making the rings endless may be adopted 50 as may be preferred. As indicated by Fig. 9, the ring spacer may be formed continuous without joint, or be a die cast ring.

In the form of the improvement as shown by Figs. 3 and 4, the saws 8 are each formed 65 with a plurality of openings 14 around the

center, and in the said openings the reduced ends 15 of cylindrical pins 16 are inserted, said pins being of such length as to extend from one saw to another and to maintain the saws in proper spaced relation. The ring spacer 5 fits over and is supported by the pins 16, as clearly shown by Fig. 4, the openings 14 and the pins 16 in engagement with said openings being at such distance relatively to the centers of the saws as to effect a positive bearing of different portions of the inner side of the rings on the group of pins therefor. The openings 14 in all of the saws 8 will be the same distance from the center of said saws, and the ring spacers 5 will be uniformly held in concentric relation to the shaft 6 upon which the saws 8 are mounted.

As shown by Fig. 5 a further modification is illustrated and consists in forming a flat pin or supporting means 17 having reduced ends 18 to engage correspondingly shaped openings 19 formed in the saws 8 and operating in the same manner as the cylindrical pins 16 shown by Figs. 3 and 4.

From the foregoing it will be seen that the supporting means for the rings may be either an integral part of the saws or separate parts engaging the saws, the object being to provide a ring spacer supporting means to hold the rings in concentric relation to the shaft of the saw cylinder for the purpose of rendering the saws of a gin saw cylinder more effective in performing their ginning operations relatively to seed cotton disposed in a roll box of a gin or in linters to remove the lint from the seeds or for any other purpose where saws arranged in cylindrical form are adapted to be used in a grouped organization. The main advantage of the improved ring spacer is that it may be constructed at a materially reduced expense relatively to similar devices heretofore used, particularly in view of the fact that there is no web extending between the same and the shaft of the saw cylinder, and for the further reason that the surface of the ring spacer is smooth and free of indentations, corrugations or other formations that have been heretofore adopted. By utilizing a part of each saw as a supporting means for the ring spacer as shown in the preferred form illustrated by Figs. 1 and 2, the cost of organization is also materially reduced and the strength and durability of the saws are not in the least impaired. The supporting means or projections are located at points sufficiently inwardly from the peripheries of the saws to avoid the least interference with the practical operation of the toothed edges or parts of the saws projecting outwardly beyond the ring spacers and which move between the ribs of the gins or linters, and this inward location of the supporting means or projections for engag- 130

ing the ring spacers obviates any weakening of the saws, particularly in view of the reinforcing effect of the ring spacers which are located exteriorly of the said supporting means or projections.

What is claimed is:

1. Gin saws having carrying means rotatable therewith and supporting means solely held thereby, combined with ring spacers between the saws and engaging the said saws around the supporting means and located outwardly and free of engaging relation to the carrying means, and also located at a considerable distance inwardly from the bases of the teeth of the saws.
2. Gin saws and supporting means held thereby, a shaft on which the saws are directly mounted, the supporting means being at a distance outwardly from the points of mounting of the saws on the shaft and held solely by and between the saws, and ring spacers having opposite edges engaging the saws and surrounding and bearing upon the supporting means in concentric relation to and free of the shaft and at a considerable distance inwardly from the bases of the saw teeth.
3. Gin saws having a shaft with which inner portions thereof directly engage and supporting means held solely by and between the saws, said supporting means having a bearing exposure at points between the inner shaft engaging portions and teeth of the saws, and band ring spacers surrounding and engaging the outer portions of the supporting means in concentric relation to the shaft and inclosing the spaces between the saws at a considerable distance inwardly from the teeth of the saws to the said shaft.
4. Gin saws, a shaft with which the saws directly engage, and ring spacers interposed between the saws and having opposite edge portions thereof directly bearing upon the side portions of adjacent saws and closing the spaces between the saws from the points of location of the spacers inwardly to the shaft, the ring spacers being held solely by the saws and clear of engagement with re-

lation to the shaft, the ring spacers being maintained in fixed applied positions solely by means held by the saws and providing bearings between the latter for the spacers.

5. Gin saws, a shaft with which the saws directly engage, ring spacers interposed between and having opposite side edges engaging the adjacent sides of the saws and fully closing the spaces between the saws, the ring spacers being free of contact with any part of the shaft and having clear spaces between the same and the shaft and also provided with outer smooth surfaces of an unbroken character, the ring spacers being maintained in positions against inward and outward movement relatively to the shaft by means held solely by and between the saws and located between the latter.

6. Gin saws having supporting means struck outwardly from intermediate portions of the body thereof, combined with ring spacers between the saws and surrounding and engaging the said supporting means.

7. Gin saws having supporting means struck outwardly from intermediate portions of the body and disposed at an angle to one side thereof, and ring spacers surrounding and engaging the said supporting means and held in concentric relation to the saws.

8. Gin saws having portions thereof struck outwardly at an angle therefrom to provide exposed bearing projections at intervals around the centers of the saws, a shaft on which the saws are mounted, and ring spacers between the saws surrounding the bearing projections out of contact with relation to the shaft, the said spacers having their opposite side edges in engagement with adjacent saws.

In testimony whereof I have hereunto set my hand in presence of two subscribing witnesses.
